C. STEINER

ROD COUPLING

Filed Feb. 3, 1923

Charles Steiner Inventor,

By *Cathcart*.

Attorneys.

UNITED STATES PATENT OFFICE.

CHARLES STEINER, OF BRISTOW, OKLAHOMA.

ROD COUPLING.

Application filed February 3, 1923. Serial No. 616,752.

To all whom it may concern:

Be it known that I, CHARLES STEINER, a citizen of the United States, residing at Bristow, in the county of Creek and State 5 of Oklahoma, have invented a new and useful Rod Coupling, of which the following is a specification.

This invention aims to provide a simple means whereby rods of the sort used in 10 well pumps may be connected and disconnected readily and rapidly.

It is within the province of the disclosure to improve generally and to enhance the utility of devices of that type to which the 15 invention appertains.

With the above and other objects in view, which will appear as the description proceeds, the invention resides in the combination and arrangement of parts and in the 20 details of construction hereinafter described and claimed, it being understood that, within the scope of what is claimed, changes in the precise embodiment of the invention shown can be made without departing from 25 the spirit of the invention.

In the accompanying drawings:—

Figure 1 shows in side elevation, a device constructed in accordance with the invention; Figure 2 is an elevation wherein the 30 device is viewed at right angles to the showing of Figure 1; Figure 3 is a cross section on the line 3—3 of Figure 1.

The numeral 1 marks a lower rod whereunto an enlarged head 2 is secured, in any desired way, the head having a thinned longitudinal fin 3, and there being inclined shoulders 4 at the upper end of the head 2, the shoulders being located on opposite sides of the fin 3. A superficial slot 5 extends longitudinally of the head 2 and is prolonged into the lower portion of the fin 3. A transverse notch 6 is fashioned in the outer edge of the fin 3, the notch being prolonged longitudinally of the fin 3 to form a bearing 40 opening 7. The lower end of a loop-shaped link 8 is pivotally mounted in the opening 7. The link 8 straddles the fin 3. The numeral 9 designates an L-shaped retainer including a shank 10 and a transverse extension 11. The extension 11 is shaped as at 12 to correspond with the outline of the bearing opening 7. The shank 10 of the retainer 9 is received in the slot 5, and the extension 11 of the retainer projects into the 50 notch 6 to hold the lower end of the link 8 in the opening 7 for swinging movement.

The shank 10 of the retainer 9 is connected to the lower end of the fin 3 and to the head 2 by a securing element 14 such as a screw. At its upper end, the fin 3 is stepped to form 60 transversely spaced longitudinal abutments 15.

The numeral 16 designates an upper rod whereunto an enlarged head 17 is secured in any desired way. The head 17 has a thinned 65 longitudinal fin 18 which at its lower end, is stepped to form transversely spaced vertical abutments 19. There are inclined shoulders 20 at the lower end of the head 17, on opposite sides of the fin 18. An opening 21 is 70 formed in the edge of the fin 18, the opening 21 being extended longitudinally of the fin 18 to form a seat 22 and to provide a projection 23 outwardly of the seat. Suppose that the rods 1 and 16 are to be coupled together. Then, the rod 1 is supported by an elevator (not shown), the elevator being engaged with the lower end of the head 2. The link 8 is swung in the direction of the arrow A in Figure 1 until it rests on the 75 shoulders 4. The rod 16 is lowered, the head 17 being disposed to the left of the head 2 in Figure 1. The upper end of the link 8 is engaged in the seat 22 which is formed in the fin 18 of the head 17. When 80 an upward pull is exerted on the rod 16, the rod 16 and the head 17 will move transversely, in the direction of the arrow B in Figure 1, until the vertical shoulders 19 on the fin 18 of the head 17 engage with the 85 corresponding shoulders or abutments 15 on the fin 3 of the head 2 as shown in Figure 1. By a reversal of the operation above described, the rods 1 and 16 may be uncoupled. It is obvious that an uncoupling and coupling of the sort above mentioned can be carried out much more readily than can the corresponding operations, when the rods are 90 threaded together, as is the prevailing practice. Should it be necessary to thrust the rod 1 forcibly in a downward direction, by pressure exerted from the rod 16, this 95 operation can be done and the rods 1 and 16 will not be separated.

What is claimed is:—

1. In a device of the class described, upper and lower coupling members, and a link pivotally mounted on the lower member, the lower member having a transverse shoulder upon which the link rests when said members are separated, the upper member being provided in one edge with an opening 100

105

110

for the reception of the link and said members being supplied with cooperating longitudinal abutments.

2. In a device of the class described, upper and lower coupling members, each including a head and a thinned fin, and a link pivotally mounted in the fin of the lower member and extended about the fin of the lower member, the head of the lower member constituting a shoulder on which the link is adapted to rest when said members are separated, the fin of the upper member being provided

in one edge with an opening for the reception of the link, and the fins of the upper and lower members being supplied at their meeting ends with coacting longitudinal abutments. 15

In testimony that I claim the foregoing as my own, I have hereto affixed my signature in the presence of two witnesses.

CHARLES STEINER.
